(57) CLAIM

The ornamental design for a polyurethane coated flooring, as shown and described.

DESCRIPTION

FIG. 1 is a top perspective view of a polyurethane coated flooring showing our new design;

FIG. 2 is a front elevational view thereof;

FIG. 3 is a rear elevational view thereof;

FIG. 4 is a bottom plan view thereof;

FIG. 5 is a right elevational view thereof;

FIG. 6 is a top plan view thereof; and,

FIG. 7 is a left plan view thereof;

FIG. 8 is an enlarged view of the selected portion 8 in FIG. 1; and,

FIG. 9 is an enlarged view of the selected portion 9 in FIG. 5.

The broken lines shown in the drawing Figures are meant to illustrate environment and form no part of the claimed design.
